ADJUSTABLE RESISTANCE

Erwin R. Stockle, Milwaukee, Wis., assignor to
Central Radio Laboratories, Inc., Milwaukee,
Wis., a corporation of Wisconsin

Application July 7, 1933, Serial No. 679,291

25 Claims. (Cl. 201—55)

This invention relates to an improvement in adjustable resistances of the type wherein a flexible contacting strip is interposed between a resistor and an adjustable pressure pad or movable contact member.

One object of the invention is to provide a compact form of adjustable resistance of this type having a maximum of effective length of resistor and a large range of adjustment and this while obtaining the advantage of a firm electrical connection and a protection of the resistor against undue or injurious abrasion.

With the type of resistor contemplated by the present invention it is usually advantageous to fabricate the resistance element initially in the form of a straight flexible strip such as a strip of cardboard or paper or other flexible material having applied thereto a resistive coating of carbon, or the like. Afterwards the strip is flexed into a curved form as, for example, a cylindrical form whereby variations in the value of effective resistance may be had by rotating an adjustable contact member or pressure pad.

With the present invention, the mounting of the resistor, its protective contacting strip and the cooperable pressure pad or movable contact is such as to provide for a substantially complete rotation of the pressure pad or movable contact member, the mounting occupying a minimum of space and thereby resulting in maximum adjustability of the resistance. Furthermore, the same means which holds the resistor in place upon its base or housing presses terminals firmly into electrical contact therewith and does this in such manner that the terminals do not interfere with the adjustable pressure pad or contact member being brought into very close proximity thereto. The structural organization is such as to facilitate easy removal and replacement of resistors whereby resistors of different values may be conveniently employed.

A further object is to provide an adjustable resistance having these advantages and capacities, which is simple and durable in construction, reliable and effective in operation, and susceptible of quantity production at a low cost.

Other objects and advantages reside in certain novel features of the construction, arrangement and combination of parts which will be herein after more fully described and particularly pointed out in the appended claims, reference being had to the accompanying drawings, forming a part of this specification, and in which:

Figure 1 is a view partly in transverse diametric cross section and partly in elevation showing an

adjustable resistance embodying the present invention, the cover plate for the housing thereof being omitted;

Figures 2 and 3 are sectional views taken on lines 2—2 and 3—3, respectively, of Figure 1, the contacting strip being omitted in Figure 3 for the sake of simplicity in illustration;

Figure 4 is a view in cross section taken on line 4—4 of Figure 2, parts being shown in elevation for the sake of illustration;

Figure 5 is a fragmentary view in cross section taken on line 5—5 of Figure 3, parts being shown in elevation for the sake of illustration;

Figure 6 is a group view in perspective illustrating the parts of the resistor prior to assembly, two of the terminals, however, being shown assembled with the insulating base or housing;

Figure 7 is a view partly in plan and partly in section showing another embodiment of the invention, the cover plate of the housing being omitted;

Figure 8 is a view in transverse cross section taken on line 8—8 of Figure 7, parts being shown in elevation for the sake of simplicity in illustration;

Figure 9 is a similar view in fragmentary cross section taken on line 9—9 of Figure 7;

Figure 10 is a view partly in transverse cross section and partly in elevation, the plane of the parts shown in cross section lying in line 10—10 of Figure 7;

Figure 11 is a plan view showing still another form of the invention, the cover plate being omitted for the sake of simplicity in illustration;

Figures 12 and 13 are views in transverse cross section taken on lines 12—12 and 13—13, respectively, of Figure 11, and parts being shown in elevation for the sake of simplicity in illustration;

Figure 14 is a fragmentary sectional view taken on line 14—14 of Figure 11 and with parts shown in elevation for the sake of illustration;

Referring to the drawings, and more particularly to Figures 1 to 6, inclusive, it will be seen that in the embodiment of the invention therein illustrated the adjustable resistance comprises a base or housing 1 of insulating material having a peripheral body portion 2 and an integral end wall 3. The open end of the housing 1 may be closed by a removable cap or closure plate, such as shown generally at 4 in Figure 6.

Within the housing 1 a resistor 5 is provided. The resistor 5 may be of any suitable type. It may be a wire wound resistor but usually and preferably it consists of a flexible strip such as

cardboard or paper or other flexible material which has a resistive coating such as carbon or the like applied to its inner face. Initially the resistor 5 is fabricated in the form of a straight flexible strip which is afterwards flexed or curved to cylindrical form to correspond in contour to the cylindrical body 2 of the housing 1 whereby it may be disposed flush up against the inner surface of the body portion 2 of this housing. In the assembly, the ends of the resistor 5 abut ribs 6 which may be molded integral with the housing 1. Terminals 7 and 8 are provided and have electrical connection with the ends of the resistor 5.

The terminals 7 and 8 are of similar construction and each has a stepped body portion 9 which, in the assembly, is snugly seated in a correspondingly formed recess 10 provided therefore in the end wall 3 of the housing 1 as shown to advantage in Figures 5 and 6. Integral with the body portion 9 of each terminal is a tang 11 of less width than its body portion 9 and which extends out through an opening 12 provided in the housing to facilitate connection of conductors with the terminals. A clamping lug 13 is integrally formed with the body portion of each terminal and is of arcuate form so as to have firm clamping engagement with the adjacent portion of the resistor 5 for the purpose of establishing electrical contact therewith and to aid, to some extent, in holding the resistor in position.

In the assembly, the clamping lugs 13 of the terminals are pressed into firm clamping engagement with the resistor and the resistor is clamped against the housing by suitable means and preferably by means of an expansible washer 15. The washer may be notched as at 15', the notches accommodating the lugs 13 and allowing the periphery of the washer to clamp the resistor against the housing. The washer 15 consists of a flat disc of insulating material, the center of which is cut out as at 16. At one point the washer 15 is split as indicated at 17. The central cut-out in the disc is bounded in part by surfaces 18 designed to coact with an expanding member as will hereinafter appear.

On the top of the washer 15 is a flanged conducting ring 20 secured in position on the washer by means of a rivet 21 which also serves to connect this ring 20 with a third terminal 22. In the assembly, the washer 15 rests flatly against the bottom wall 3 of the housing 1 and its terminal 22 projects exteriorly of the housing through an opening 23 provided therefor. The washer 15 is centered or located in proper position in the assembly by means of a centering or locating pin 24 which may be molded integral with the end wall of the housing and which projects up through the split 17 of the washer and through a notch 25 in the ring 20.

A flexible contacting ring 26 is provided and may be formed from a strip of suitable flexible metal, the strip being bent into circular form and has its ends overlapped and soldered or otherwise suitably secured together. A slot 27 is formed in the overlapped ends of the strip and receives a tongue 28 integral with the flange 20' of the ring 20. The lower edge portion of the ring 26 is inwardly curved as at 26' so as to be interlocked with the correspondingly curved flange 20' of the ring 20. The interengagement of the curved edge 26' and the engagement of the tongue 28 with the slot 27 holds the strip 26 against axial displacement while leaving the same free to be

deformed radially outward into contact with the resistor 5 throughout the extent of the strip.

Substantially any portion of the flexible contact strip 26 may be pressed into engagement with the conductive coating of the resistor 5 by means of a pressure pad or button 30 of insulating material carried by a spring arm 31 of arcuate form, one end of which is riveted or otherwise suitably fastened to the outer end of a radial arm 32. The arm 32 is riveted or otherwise fixed to the inner end of a rotatable shaft 33, the outer end of which carries a knob 34 whereby it can be conveniently turned. The shaft 33 is rotatably fitted in a mounting bushing 35 which extends through the cut-out or opening in the washer 15 and through an opening 38 provided therefor in the end wall 3. Adjacent its inner end this mounting bushing 35 has a shoulder 36 which, in the assembly, abuts the apertured plate portion 37 of a stop finger 38. The inner portion of this bushing 35 is threaded to receive a nut 40. Between the threaded portion 39 of the bushing 35 and the shoulder 36 the outer periphery of the bushing is smooth and tapered as at 41. When the nut 40 is tightened up the tapered portion 41 is pulled through the washer 15 and engages the surface 18 to expand the washer thereby causing the periphery of the washer to press against the lugs 13 and cause these lugs to have clamping engagement with the resistor to secure the same in place and establish electrical contact between the terminals and the resistor. The shoulder 36 holds the stop plate 37 and washer 15 in position and as the flexible contacting strip 26 is interengaged with the contact ring 20 and as the latter is fastened to the washer 15, the contact ring 20 is also held in position. Thus, a single fastening means, the nut 40, secures all of the parts in proper assembly and provides for the easy removal and replacement of any of these parts. It will be understood that the stop finger 38 is engageable with the arm 32 to limit the rotation of this arm in either direction. Lugs 37' on the plate 37 engage the shoulder 36 and in a recess 3' in the end wall 3 to locate the stop finger 38 and to secure the bushing 35 against turning. Stop finger 38 also extends through slot 43 in the cover 4 and on being bent at a right angle serves to prevent the cover from coming off.

The arm 32 is shown as provided with a projection 32' utilized in many instances for interlocking the adjustable resistance with a switch mechanism (not shown) but as the switch mechanism and interlocking feature form no part of the present invention they need not be described.

In the embodiment of the invention shown in Figures 7 to 10, inclusive, the housing 1, resistor 5, expansible washer 15 and intermediate contacting strip 26 are substantially the same and assembled in substantially the same manner in the previous embodiment of the invention and bear corresponding reference numerals. However, the contact ring 20 is omitted and a different mounting is employed for the intermediate contacting strip 26. As shown in Figures 7 and 9 the terminals 7' and 8' for the resistor 5 may be provided with lugs 7a and 8a firmly clamped against the resistor 5 by the expansible washer 15. As illustrated in Figures 7 and 10, the contacting strip 26 has its overlapped ends secured by means of a rivet 50 to the upstanding portion 51 of the third terminal 53 which is fitted in and projects beyond an opening 54 provided therefor in the housing.

The adjustable contact means or pressure pad 75

in this embodiment includes as before a shaft 33 rotatably mounted in a bushing 35 held in position by means of a nut 40 and having a tapered or inclined portion 41 for expanding the washer 15 in this form of the invention. However, the pressure pad 30, its spring arm 31 and radial arm 32 are omitted and in lieu thereof a rotatable ring 55 is provided and has its hub 56 appropriately fastened to the inner end of the shaft 33. The radial arm 57, which is integral with and connects the hub with the ring 55, is provided with a radial socket or recess 58 in which a pressure pad or button 59 is slidably fitted. A spring 60 urges the pad or button outwardly.

It is to be understood that the ring 55, its hub 56 and the arm 57 may be molded from suitable insulating material, such as phenol condensate composition or the like.

20 In the embodiment of the invention shown in Figures 11 to 14, inclusive, the insulated base or housing is designated generally at 61 and has flaring side walls of body portion 61' with an integral end wall 62 at the small end thereof. The open end of the housing may, as in the previous embodiments, be closed by a removable cap or closure. A resistor 63 in the form of a carbon coated flexible strip or the like is fitted against the inner surface of the body portion 61 of the housing and is held in proper position thereagainst by means of an expansible washer of insulating material designated at 15' and corresponding in structure and operation to the washer 15 of the embodiments previously described, in 30 that it is split as shown at 64 and is expanded to cause lugs 65 of the terminals 66 to clamp the resistor in position. As in the previous embodiments a mounting bushing 35 having a tapered portion 41 acts under the influence of a nut 40 to expand the washer 15'.

In the present embodiment of the invention a conducting ring 67 is held in position on the washer 15' by the action of the bushing 35 exerted through a washer 68' and by means of a rivet 68 which secures the ring and a terminal 69 to the washer and electrically connects the ring and terminal. An intermediate contact strip 70 is provided and is of conical form, the lower and smaller end of the strip 70 being engaged with a correspondingly formed flange 67' of the ring 67, and being further held in position by means of a lug 71 integral with the ring 67 and extending through an opening or slot 72 in the strip.

55 To the inner end of the shaft 33 a movable contact arm 73 is riveted or otherwise securely fixed. This arm 73 is of resilient metal and carries at its outer end a contact button or pad of insulating material. The arm 73 is so bent and flexed or tensioned that under the influence of its inherent resiliency the button or pad 74 presses against the contacting strip 70 whereby the portion of the strip engaged by the pad or button will be deformed or flexed outwardly into contact with the resistor as will be understood from Figures 11 and 12. A stop finger 75 is provided and is engageable with the arm 73 for positively limiting its movement in either direction. The finger 75 has an integral attaching plate 76 confined between nut 40 and the housing 61 and the intermediate portions of the finger 75 passes through opening provided therefor in the end wall 62 of the housing, the washer 15' and the conducting ring or disc 67.

75 In all of the embodiments of the invention the

advantages of compactness, simplicity and economical manufacture, along with efficiency in operation and durability, are realized. Furthermore, the elements of the adjustable resistance are organized in such a novel manner as to be conveniently assembled and disassembled for the purposes of replacement or repair. Along with these practical advantages there is preserved the features of protecting the resistor from undue abrasion upon adjustment and of obtaining a large range of adjustment and utilizing a maximum of effective length of resistor.

The invention lends itself to the use of any desired number of terminals and, if desired, to the use of the so-called tap terminals. The several modifications may be employed singly or in multiple as desired. For example, several units of the same type may be clamped together and simultaneously operated. In the forms of the invention utilizing the contact rings such as the contact ring 20 (Figures 1 to 6) or the contact ring 67 (Figures 11 to 14) the third terminal may be omitted or not used and the contact ring may be grounded by connecting it to the bushing 35.

While I have shown and described several constructions in which the invention may be embodied, it is to be understood that the constructions shown have been selected merely for the purposes of illustration and that various changes in the size, shape and arrangement of the parts and in the materials employed may be resorted to without departing from the spirit of the invention or the scope of the subjoined claims.

The invention claimed is:

1. An adjustable resistance comprising a housing, a resistor disposed therein, terminals engageable with said resistor for establishing electrical contact therewith, a member within the housing for pressing said terminals against the resistor, means for securing the member in position in the housing and having an expanding action on said member to press the terminals against the resistor, and adjustable contact means cooperable with said resistor, said member securing means also providing a mounting for the adjustable contact means.

2. An adjustable resistance comprising a housing, a resistor disposed against a wall thereof, terminals engageable with said resistor for establishing electrical contact therewith, a deformable member insertable in the housing and engageable with the resistor substantially throughout its peripheral extent and also with said terminals to clamp them against the resistor and to clamp the resistor against said housing and means for deforming said member and securing it in position in the housing.

3. An adjustable resistance comprising a housing, a resistor disposed against a wall thereof, terminals engageable with said resistor, a deformable member engageable with said terminals to clamp them against the resistor, adjustable contact means cooperable with said resistor, a mounting for said adjustable means, said mounting, in its operative position, being cooperable with said deformable member to deform the same to press the terminals against the resistor, and means for securing said mounting in operative position in said housing.

4. An adjustable resistance comprising a housing, a resistor disposed within the housing and comprising a strip and resistance means carried thereby, terminals projecting exteriorly of the housing and having portions therein overlapping the inner surface of the resistor, a disc-like ex-

5
pansible member within the housing, and having peripheral engagement with the last named portions of the terminals, means for expanding said member into edgewise abutting engagement with the portions of the terminals overlapping the resistor to clamp the terminals against the resistor, and adjustable contact means cooperable with said resistor.

10
5. An adjustable resistance comprising a housing having a curved interior wall, a resistor disposed in the housing against and conforming to the curvature of said wall and comprising a strip carrying resistance means thereon, an adjustable contact means cooperable with said resistor and disposed in the housing for rotation about an axis substantially co-axial with the said curved interior wall, an expansible washer in the housing in transverse relation to said axis and having peripheral engagement with said resistor, and means for expanding the washer in the plane thereof to clamp the resistor against said wall.

15
20
25
30
6. An adjustable resistance comprising a housing, a resistor disposed within the housing and against a wall thereof, an expansible washer in said housing, means for expanding said washer to cause it to clamp said resistor against the wall of the housing, a flanged contact member carried by said washer, a contact strip interengaged with the flange of said member and overlying said resistor and adjustable means for pressing various portions of said strip along its length into engagement with said resistor.

35
40
45
50
7. An adjustable resistance comprising a housing, a resistor disposed within the housing and against a wall thereof, an expansible washer in said housing, a mounting bushing having a tapered portion engageable with the expanding washer, means coacting with the bushing for causing said tapered portion to expand the washer, and adjustable contact means supported on said mounting bushing and cooperable with said resistor.

45
50
55
60
8. An adjustable resistance comprising a housing, a resistor disposed within the housing, a contact ring fixed in said housing, terminals for said resistor and said contact ring, a flexible contact strip overlying said resistor, said contact strip and said contact ring lying in different planes and having portions loosely, but positively interengaged to prevent axial shifting of the contact strip while providing for lateral displacement thereof, means for preventing bodily displacement of said contact strip, and adjustable contact means cooperable with said strip for displacing portions thereof into engagement with said resistor.

65
70
9. An adjustable resistance comprising a housing, a resistor disposed within the housing, a flanged contact ring fixed within the housing, terminals for said resistor and said contact ring, a contact strip overlying the resistor in transverse relation to said contact ring and having a portion engageable with the flange of said contact ring, means for preventing bodily displacement of said contact strip and adjustable pressure means cooperable with said strip for displacing portions thereof into engagement with the resistor.

75
10. An adjustable resistance comprising a housing, a resistor disposed within the housing, a contact member fixed within the housing, terminals for the resistor and the contact member, a contact strip overlying said resistor, said contact member and said contact strip having por-

tions at least of approximately conical form, said portions being interengaged to hold the contact strip against axial displacement while providing for lateral outward displacement thereof, and adjustable pressure means cooperable with said strip for displacing portions thereof laterally outward and into engagement with said resistor.

means for expanding said member and securing it in position in the housing.

16. An adjustable resistance comprising a housing having a curved interior wall, a flexible resistor strip bent to correspond to the curvature of the wall and disposed flush thereagainst, terminals having portions engageable with the resistor, an expansible member in said housing, acting when expanded to press the terminals against the resistor to secure the same in position and establish electrical connection therewith, means for expanding said member, in combination with a contacting strip overlying the resistor, means for holding the contacting strip in position while providing for outward displacement of portions thereof into engagement with the resistor, and an adjustable pressure means for displacing various portions of the contacting strip into engagement with the resistor, said expansible member serving as a part of the mounting for the adjustable pressure means.

17. An adjustable resistance comprising a housing having a curved interior wall, a flexible resistor strip bent to correspond to the curvature of the wall and disposed flush thereagainst, terminals having portions engageable with the resistor, an expansible member in said housing, acting when expanded to press the terminals against the resistor to secure the same in position and establish electrical connection therewith, means for expanding said member, in combination with a protective contacting strip, means for securing said contacting strip to the expansible member to prevent axial movement thereof while providing for outward lateral displacement of portions of said contacting strip, and adjustable pressure means for displacing various portions of said contacting strip into engagement with various portions of the resistor.

18. An adjustable resistance comprising a housing, a resistor disposed within the housing and against the wall thereof, an expansible washer in said housing, a contacting strip overlying the resistor, means carried by said expansible washer for holding the strip against bodily displacement while providing for outward lateral displacement of portions thereof into engagement with the resistor, a rotatable pressure pad for displacing portions of said strip into engagement with the resistor, a mounting for said rotatable pressure pad, and means cooperable with the housing for releasably securing said mounting in position, said mounting having means for expanding said washer to secure the resistor in position and also to secure the washer in position.

19. An adjustable resistance comprising a housing, a resistor disposed within the housing and against the wall thereof, an expansible washer in said housing, a contacting strip overlying the resistor, means carried by said expansible washer for holding the strip against bodily displacement while providing for outward lateral displacement of portions thereof into engagement with the resistor, a rotatable pressure pad for displacing portions of said strip into engagement with the resistor, a mounting for said rotatable pressure pad, and means cooperable with the housing for releasably securing said mounting in position, said mounting having means for expanding said washer to secure the resistor in position and also to secure the washer in position, in combination with a stop secured in position in said housing by said mounting.

20. An adjustable resistance comprising a housing having a curved interior wall, a resistor

disposed within said housing against said wall and bent to correspond to the curvature thereof, a contacting strip overlying the resistor, means for holding the contacting strip against bodily movement while providing for displacement of portions thereof entirely about the strip into engagement with portions of the resistor, a rotatable member mounted in said housing within said curved interior wall, a spring arm carried by said rotatable member and a pressure pad carried by said arm and engageable with the contacting strip for displacing portions thereof into engagement with portions of said resistor, the resistor and the contact strip being arranged with their engageable surfaces in substantially parallel relation to each other and to the axis of rotation of said rotatable member.

21. An adjustable resistance comprising a housing, a resistor disposed within the housing and insulated therefrom, terminals electrically connected to the ends of said resistor, a conducting disc of smaller diameter than the inside diameter of said resistor mounted within the confines of the latter in spaced relation thereto and concentric therewith, the periphery of said disc and the opposed surface of said resistor defining spaced contact surfaces, a flexible conducting ring loosely fitting about said disc between the latter and said resistor, a terminal electrically connected to said disc, and adjustable means adapted to flex said ring into firm contact with said resistor at a variable location along the latter and simultaneously to engage said ring in firm though correspondingly variable contact with the peripheral contact surface of said disc whereby the resistance between said last mentioned terminal and either of said first mentioned terminals may be varied.

22. An adjustable resistance comprising a housing, a resistor in the form of an annulus disposed within the housing and insulated therefrom, terminals electrically connected to the ends of the resistor, a conducting member mounted within the housing and having an arcuate contact surface of smaller diameter than the inside diameter of the resistor disposed within the latter in spaced relation thereto and concentric therewith, a terminal electrically connected to said member, a flexible contact strip fitting about said arcuate contact surface between the latter and the resistor, and adjustable pressure means for flexing the strip into firm contact with the resistor at a variable location about the latter, said strip having a loose connection with the arcuate contact surface of the conducting member whereby the strip under the action of the pressure means will retain firmly contact with the arcuate contact surface as to one portion of the strip as the other portion is displaced from the member into contact with the resistor.

23. A resistance comprising a housing having a circular wall, a resistor comprising a flexible backing strip having a resistive coating applied to one face thereof, said strip being flexed in the assembly with its backing strip disposed against the circular wall of the housing and with its resistive coating spaced from said wall, a clamping member in said housing and having a substantially circular periphery engaged with the resistor for substantially the entire length thereof, means for causing the clamping member to clamp the resistor between its periphery and the circular wall of the housing throughout substantially the entire length of the resistor, and

adjustable contact means cooperable with the resistor.

24. A resistance comprising a housing having a circular wall, a resistor comprising a flexible backing strip having a resistive coating applied to one face thereof, said strip being flexed in the assembly with its backing strip disposed against the circular wall of the housing and with its resistive coating spaced from said wall, terminals engageable with the resistive coating of the resistor for establishing electrical contact therewith, and a clamping member having a circular periphery engaged with a portion of the resistor for substantially the entire length thereof and also engaged with the terminals, means for causing the clamping member to clamp the resistor between its periphery and the circular wall of

the housing and also to clamp the terminals against the resistor, and adjustable contact means cooperable with the resistor.

25. A resistance comprising a housing having a curved wall, a resistor comprising a flexible backing strip having a resistive coating on a surface thereof, said resistor being flexed in the assembly with its back disposed against said curved wall of the housing, a clamping member disposed in the housing and having a curved periphery engaged with a portion of the resistor for substantially the entire length thereof, and means associated with the housing for causing the clamping member to clamp the resistor between itself and the housing for substantially the full length of the resistor. 5

ERWIN R. STOEKLE.
